WINDOW SASH HOLDER

Erick Albert Johnson, Kenosha, Wis.

Application August 10, 1936, Serial No. 95,265

1 Claim. (Cl. 292—275)

This invention relates to a window sash holder, more particularly to a sash holder for windows of the casement type.

The primary object of the invention is to provide means for securely holding a hinged window or the like open to any extent desired, which extent of opening may be freely varied at will.

A further object of the invention is to provide a holder of the character aforesaid which may be economically stamped from metal or any other suitable material, and which may be readily applied to installed windows without any alterations in the existing structure thereof.

An embodiment of the invention is illustrated in the accompanying drawing in which—

Figure 1 is a front elevation of a window showing the invention in association therewith,

Figure 2 is a side elevation of the structure shown in Figure 1, with a dotted line showing of the sash held partially open,

Figure 3 is an enlarged elevation of the elements forming the holder in assembled relation,

Figure 4 is an elevation of the assembled elements of the holder as viewed from the left of Figure 3,

Figure 5 is a section taken on the line indicated 5—5, Figure 4,

Figure 6 is a detail in elevation of one of the clamping elements of the holder, and

Figure 7 is a horizontal sectional view of a modified form.

Referring to the drawing in detail, the numeral 1 indicates a window frame having a sash 2 hinged thereto at the top of the sash. While the window and sash herein shown are of the type commonly used in basements and attics, the holder may be applied with equal facility to a sash which is hinged at one side or at the bottom.

Fixedly secured to the frame 1 by suitable holdfast devices, such as the screws 3 is the base of an angular bracket 4 having an arm 5 projecting from the frame at a right angle thereto. Having one end pivoted to the arm 5 of the bracket 4 is a flat elongated bar 6.

Fixedly secured to the sash 2 by suitable holdfast devices is the base of an angular bracket 7 having a leg 8 projecting at a right angle to the plane of the sash in slightly overhanging relation to a side edge thereof. A flat clamping member 9 is provided at one side with a flange 10 turned in spaced relation to the body of the clamp to provide a recess 11 adapted to receive a side portion of the bar 6 therein. At the opposite edge of the member 9 is a flange 12 of a thickness equal to the width of the recess 11. Interme-

diate the flange 12 and recess 11, the member 9 is provided with a polygonal opening 13.

When the parts are assembled a polygonal portion 14 of a bolt indicated generally at 15 extends through the opening 13 in engagement with the walls thereof and in engagement with one edge face of the bar 6, the opposite edge of the bar being disposed within the recess 11. Lying flat against the flange 12 and bar 6, and interposed between the flange and bar and the leg 8 of the bracket 7, is a washer 16 which seats on the bar 6 and flange 12. The bolt 15 extends through washer and through an opening 17 in the leg 8 and is provided at its projected end with a wing nut 18. The inner edge of washer 16 and the opening 17 align with the opening 13.

When the holder is assembled in connection with a sash and frame, and it is desired to adjustably open the sash, the nut 18 is loosened to permit sliding movement of the bar with respect to the clamping member 9, washer 16 and leg 8 of the bracket 7. Upon manually moving the sash about its hinged connection, the bar 6 swings about its pivotal connection with the arm 5 of the bracket 4, and also slides with respect to the bracket and clamp assembly secured to the sash. When the nut 18 is tightened the bar 6 is firmly clamped between the member 9 and washer 16 with the polygonal portion 14 of the bolt engaging the walls of the opening 13 and also engaging one edge face of the bar 6, the opposite edge of the bar being engaged by the wall of the recess 11. Thus it will be seen that when the nut 18 is tightened, both sliding and turning movement of the bar 6 is prevented.

With reference to the modification shown in Figure 7, the clamping member of the holder is indicated at 19 and it is formed with inclined side flanges 20, 21. The bar 6 extends through the member 19. The flange 20 opposes a side edge of bar 6. The member 19 has an opening 22 for the passage of bolt 15 which carries nut 18. The bolt 15 also extends through the leg 8 of the bracket 7. Interposed between said portion 8 and bar 6 is a cup-shaped washer 23 which not only seats on bar 6 but also on flange 22.

Although but one washer 16 is shown, it is to be understood that two or more may be employed. The washers 16 and 23 constitute spacers and are used to obtain the space needed between frame of window and sash and also to clear the square on the bolt as the nut will not go down that far. Owing to the arrangement of either of the spacer washers with respect to the bar 6 and a clamp the canting of the latter and the bar 6, as well

as the twisting of the latter is prevented when the nut is screwed home.

It is to be understood that the above description and referred to illustration of the invention represent a practical and preferred embodiment of the same, and that changes in the details of construction may be resorted to so long as such changes fall within the scope of the invention as defined in the appended claim.

10 10 What I claim is:—

In a holder for adjustably holding open a hinged window sash with respect to a window frame, said holder comprising a bracket adapted to have its base anchored to the frame and including an arm extended from said base, a bracket adapted to have its base anchored to the sash and including a leg extended from the base, a clamping element provided with side flanges and opposing one face of and disposed lengthwise with

respect to said leg, a bar pivoted at one end of said arm, extending between said leg and element, seated on the latter and arranged in close proximity to one and spaced from the other of said flanges, a spacer member for said element bearing respectively against the said face of said leg, one face of said bar and the said other of said flanges, a bolt extending through said leg, element and member and positioned between said bar and the said other of said flanges, and a 10 clamping nut coacting with the bolt for clamping said bar, element and member stationary to said leg when positioned at a selected point of said bar, said element and bolt having coacting means to prevent the turning of the bolt relative to said 15 element, leg and member, the coacting means on said bolt bearing against a side edge of said bar.

ERICK ALBERT JOHNSON.
